UNITED STATES PATENT OFFICE.

WILLIAM ALBERT HICKMAN, OF WEST MYSTIC, CONNECTICUT,

BOAT.

Application filed December 2, 1922, Serial No. 604,596, and in Colombia, South America, October 23, 1922.

This invention pertains to improvements in boats, and more particularly, though not exclusively, to improvements in boats of the type described in United States Letters Patent No. 1,204,355, issued to me November 7th, 1916.

In the drawings, which show a preferred form of one embodiment of my invention:

Figure 1 is a side elevation of a hull in which the center keel, throughout the greater part of the boat, is above the level of the chines at the side of the boat;

Fig. 2 is a view on an enlarged scale to show clearly the peculiar curve of the keel line and of the chine lines adjacent the stern of the boat to provide an increasing angle of incidence aft;

Fig. 3 is a plan view of the hull which has generally straight and perpendicular sides, being generally rectangular in plan but in which the stern is angled somewhat to permit play of the rudders in opposite directions;

Fig. 4 is a rear elevation of the board which constitutes the bottom of the stern of the boat;

Figs. 5, 6, 7 and 8 are diagrammatic sections through the bottom of the boat on the lines 5-5, 6-6, 7-7, and 8-8, respectively, of Fig. 3;

Fig. 9 is a plan taken below the section line 9-9 of Fig. 10, and shows the preferred double-acting side plate rudders connected to be operated conjointly in both directions and preferably, as illustrated, inclined relative to the central longitudinal plane of the boat; and

Fig. 10 is a rear elevation of the stern of the boat, being partly in section.

Referring to the drawings, and to the preferred form of my invention selected for illustrative purposes, I have disclosed a boat of the inverted V-bottom type which is the subject-matter of my United States patent above referred to, presenting a hull generally rectangular in plan and having the keel 11 located above the chines 12, from which the sides rise substantially vertically, the elevation of the keel above the chines being greatest adjacent the bow, as shown in Fig. 8, and gradually decreasing toward the stern of the boat, as shown in Figs. 7, 6 and 5.

The bottom of the boat is preferably flat at the stern proper, being presented by the bottom of the stern plank 13 shown in Fig. 4.

55

In boats of this inverted V-bottom type where sufficient power is provided for propulsion in proportion to the weight and under surface, the hull will rise in the water as speed is increased until, in the relatively light high-power racing types of boat, the boat practically rides on its chines at the sides and on its extreme stern, with very little submergence. This raising of the hull in boats of the inverted V-bottom type, as illustrated in my patent above referred to, does not take place evenly as speed is increased, there being a tendency, in boats of the earlier type referred to shown in said patent, for the bow to rise while the stern is depressed so that the boat plows through the water, making a very considerable commotion, and being very inefficient until sufficient speed is attained so that the stern will rise and the boat will proceed on a generally even keel.

60

This to some extent limited the efficient use of boats of the inverted V-bottom type to those having very great power in proportion to weight. It is among the objects of the present invention to greatly increase the efficiency of this type of boat under all circumstances, and particularly to improve its action where the power applied, in proportion to the weight, is not sufficient to raise the hull so much out of the water as above described. This feature of my invention also serves in boats of the inverted V-bottom type to prevent the depression of the stern when operated at relatively low speeds, and to keep generally on an even keel fore and aft, boats travelling at relatively high speeds, in which the weight in proportion to bottom area and power available are suited for commercial purposes as distinguished

65

from pleasure or racing craft.

70

I have found that the depression of the stern in my earlier boats of the inverted V-bottom type was due to the fact that the bottom adjacent the stern presented an angle of incidence with which the proper distribution of supporting surface fore and aft was not attained and which coupled with the adhesion of the water and the atmospheric pressure overcame the lifting tendency oc-

75

80

85

90

95

100

casioned by forward movement of the boat until a very considerable speed was attained with attendant proper distribution of supporting surface relative to weight. By providing, as in the invention shown in the present application, surfaces on the bottom of the boat aft in which the angles of incidence increase, the stern is not only prevented from lowering at very low speeds, but is raised to the desired position to maintain the boat on a generally even keel fore and aft at a much lower speed than where these increasing angles of incidence are not provided. The increased angle of incidence aft elevates the stern even at low speeds thus preventing the bow from rising to an undesirable extent, and presenting submerged sections much easier to advance through the water than heretofore. The underwater section presented not only has a decreased maximum cross-sectional area, but presents to the water surfaces angles to provide an improved resolution of forces, both lifting and advancing, the adhesion of the water and the drag from atmospheric pressure both being reduced.

In Fig. 1 of the drawings, the line of the keel 11 is indicated in dotted lines, while the line of the chines 12 is indicated in full lines. The increasing angles of incidence in the preferred form of my invention illustrated are provided by reversely curving the keel line adjacent the stern, so that the line of the keel, curving upward at the bow, curves in a reverse direction adjacent the stern, as is best shown in Fig. 2, which is on an enlarged scale. I have also found that the advantages attendant to these increasing angles of incidence are best supplied by providing aft a similar reverse curve of the chines, this reverse curve of the chines being preferably somewhat less than the reverse curve of the keel so that the two may meet at the stern 13 of the boat in a straight line, or a substantially straight line transversely considered as distinguished from the angled stern line presented in the construction shown in my United States Patent 1,204,355 referred to, and directed to the earlier type of inverted V-bottom boat.

Where, as in the present application, one or more surface propellers 15 are used, the advantages of the general type of hull herein shown are particularly availed of because the hull, maintaining a generally normal position fore and aft even at low speeds or when heavily loaded, delivers from beneath the stern of the boat the practically flat sheet of water in which these propellers act most efficiently. While the increasing angle of incidence may be provided in hulls in which the stern line 13 is not straight, and even when so used has advantages particularly in connection with the surface propellers, I have found that the surface pro-

pellers act more efficiently where the stern line is straight as distinguished from angled. The surface propellers of the boat shown in the present application have their hubs practically touching the water as distinguished from elevated considerably above the water in my patent above referred to. This lowering of the propeller hubs not only increases the depth of dip of the propeller or propellers of any given diameter, but enables me to increase the efficiency for any given dip, because as the diameter of the propeller is decreased, without decreasing the working area, the speed at which the propellers may be efficiently driven, and the average amount of blade immersed at all times, is materially increased. While for some arrangements a single surface propeller is desirable, I prefer to use multiple propellers and in the present application I have shown these as four in number, of which the outer two are somewhat longer than the inner two, so that the water acted upon by the propellers considered as a whole will present fewer counter-acting currents and so that the opportunity for cavitation will be reduced.

As the boat passes through the water, substantially all spray is thrown inwardly, being caught in the V-shaped recess between the chines and the keel, considerable air also being entrapped so that the boat as it proceeds at high speed is riding to a considerable extent on a cushion of air and spray resulting in a well distributed positive pressure under the bottom aft of the forward waterline. In a boat of ordinary V-bottom type, as distinguished from the inverted V-bottom type, the tendency of the hull is to move the water laterally not only above the surface where it takes the form of spray, but below the surface where each particle, dragged forward somewhat by the hull, has a lateral movement which tends greatly to decrease the speed of the boat not only because of energy unnecessarily used in moving the water, but because of the negative pressure, engendered by the lateral outflow, on the bottom surface of the boat when travelling at any considerable speed. In boats of the type here under consideration, there is little or no tendency to move the particles of water laterally, the tendency being rather to move the particles downwardly and the reaction of this contributes to the lifting of the boat so that power ordinarily wasted in moving water uselessly is here to a very considerable extent utilized in elevating the hull so that the resistance of the boat to forward movement is decreased and, considering the factors of weight and speed, considerable power is saved. The increasing angle of incidence adjacent the stern of the boat, as herein described, materially adds to the improved effect of lifting the boat because the lifting

is more uniform than in my earlier type of inverted V-bottom boat, the reaction of the water adjacent the stern tending to lift the boat being materially increased.

5 Where, in my earlier patent, I have shown twin rudders to be operated one at a time to turn the boat, I have found that by operating the rudders conjointly, by adapting them to swing in either direction together, the 10 steering is markedly improved, there being less retardation of the boat in connection with turning at any given speed at a given radius by the combined action of the two rudders than by the action of the rudder at 15 the inside of the curve only, as in my other patent referred to. The operation of the rudders is best shown in Fig. 9, wherein the rudder-controlling shaft 20 is provided at an outer end with a pinion 21 meshing 20 with the rack 22, which is connected by rods 23, 23 with the rudders 24, 24. The action of the rudders 24, 24, cooperating to turn the boat, also tends to tip the boat laterally toward the inside of the curve, while opposing 25 any tendency to slip or skid arising from the contact of the water with the bottom of the boat. This anti-skid action is materially increased, turning power is increased and retardation diminished by inclining the 30 pivots 25, 25 on which the rudders are swung, inwardly toward their top so that the rudders are angled relative to each other when viewed from the stern, as shown in Fig. 10. Thus if the rudders, as viewed in 35 Fig. 10, are swung to the right with a view to turning the boat to the right, the rudder at the right-hand side of Fig. 10 will promptly undercut the water, tending to drag down the inner or right-hand side of the boat, 40 while the other rudder at the left of Fig. 10 will, by reason of the angle at which it cuts the water, tend to raise the left-hand side of the boat, thus contributing to the banking of the boat during turning, while 45 also contributing its share to the turning moment.

It will be understood that with a view to permitting the rudders to be swung in both directions, I have altered somewhat the 50 shape of the sides of the boat adjacent the stern from the construction illustrated in my earlier patent, so that the sides of the stern, instead of being square, are angled at 55 26, 26. The axes of the rudder pivots 25, 25, as illustrated, lie in a common plane extending transversely to the boat and generally vertical relative thereto. This angle may for some purposes be varied in one 60 direction or the other, but I have found that where the rudders are angled as viewed from the stern (Fig. 10) it is unnecessary, and even perhaps undesirable, to angle the pivots of the rudder as viewed from the sides 65 of the boat.

65 While I have shown and described a pre-

fferred form of one embodiment of my improved boat, it will be understood that various features thereof are useful separately and that considerable changes in structure and in the combination may be effected without departing from the scope of my invention which is best defined in the following claims. 70

I claim—

1. A boat presenting a bottom of the inverted V-bottom type in which the angles of incidence increase aft. 75
2. A boat presenting a bottom of the inverted V-bottom type in which the angles of incidence of one or more surfaces increase aft. 80
3. A boat having a hull with sides free of inward inclination or tumble-home and a bottom presenting inverted V sections gradually broadening aft, the bottom presenting increasing angles of incidence aft. 85
4. A boat having a hull with sides free of inward inclination or tumble-home and a bottom presenting inverted V sections gradually broadening aft in which the angle of incidence of one or more surfaces increases aft. 90
5. A boat having a hull with sides free of inward inclination or tumble-home and a bottom presenting inverted V sections gradually broadening aft, the bottom presenting adjacent the stern a surface having a greater angle of incidence to the water than surfaces nearer the bow. 95
6. A boat of the gliding or semi-gliding type having a propeller, the hub of which when the boat is at speed lying above the level of the sheet of water immediately behind the boat and in which the bottom presents increasing angles of incidence aft. 100
7. A boat in which the keel is generally above the level of the chines presenting an inverted V-bottom section between the chines, the angles of the bottom sections where they meet at the keel gradually becoming more and more obtuse toward the stern, the keel curving adjacent the stern to present increasing angles of incidence to the water. 105
8. A boat in which the keel is generally above the level of the chines presenting an inverted V-bottom section between the chines, the angles of the bottom sections where they meet at the keel gradually becoming more and more obtuse toward the stern, the chines curving adjacent the stern to present increasing angles of incidence to the water. 110
9. A boat in which the keel is generally above the level of the chines presenting an inverted V-bottom section between the chines, the angles of the bottom sections where they meet at the keel gradually becoming more and more obtuse toward the stern, the keel and chines curving adjacent 115
10. A boat in which the keel is generally above the level of the chines presenting an inverted V-bottom section between the chines, the angles of the bottom sections where they meet at the keel gradually becoming more and more obtuse toward the stern, the keel and chines curving adjacent 120
11. A boat in which the keel is generally above the level of the chines presenting an inverted V-bottom section between the chines, the angles of the bottom sections where they meet at the keel gradually becoming more and more obtuse toward the stern, the keel and chines curving adjacent 125
12. A boat in which the keel is generally above the level of the chines presenting an inverted V-bottom section between the chines, the angles of the bottom sections where they meet at the keel gradually becoming more and more obtuse toward the stern, the keel and chines curving adjacent 130

the stern to present increasing angles of incidence to the water.

10. A boat having a hull with sides rising substantially vertically from lateral chines and a bottom between the chines formed as a single concavity presenting inverted V sections gradually flattening aft and having

twin rudders hung aft, the axes of which lie in upwardly converging planes longitudinal of the hull.

In testimony whereof, I have signed my name to this specification.

WILLIAM ALBERT HICKMAN.
